DETACHABLE ELECTRIC CONNECTOR

Guy O. Robinson and George K. Robinson,
Oakland, Calif.

Application May 16, 1938, Serial No. 208,216

3 Claims. (Cl. 173—330)

The invention relates to detachable electric conductors of the type commonly used for making an electric connection through a so-called wall plug and socket or "convenience outlet" and for use in electric extension circuits, where the connector is generally composed of a plurality of sections which may be attached when in use and detached when no electric current is being drawn.

An object of the present invention is to provide a detachable electric connector of the character described having a plurality of detachable sections which may be quickly and readily attached in an improved manner facilitating the attachment of the sections when the male and female parts of the section are not conveniently visible for attachment.

Another object of the invention is to provide a detachable electric connector of the character above having an improved form of construction rendering the same more rugged and sturdy and better able to withstand rough and long-continued use than similar connectors heretofore available.

A further object of the invention is to provide an electric connector of the character above which will ensure an improved electric connection between the contact members of the connector and provide the firm, tight engagement of the respective contact members throughout a long period of use.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

Referring to said drawing:

Figure 1 is a longitudinal sectional view of a detachable electric connector constructed in accordance with the present invention.

Figure 2 is a cross-sectional view of the connector illustrated in Figure 1 and is taken substantially on the plane of line 2—2 of Figure 1.

Figure 3 is an end elevation of one of the connector sections.

Figure 4 is a side elevation of the connector with one of the sections shown in cross-section and illustrating the detachable parts in substantially detached position.

Figure 5 is a longitudinal sectional view simi-

lar to Figure 1 but showing a modified form of the connector.

Figure 6 is a cross-sectional view of the connector illustrated in Figure 5 and is taken substantially on the plane of line 6—6 of Figure 5.

The electric connector of the present invention and as illustrated in the accompanying drawing, comprises a plurality of sections 8 and 9, each provided with electric contact members 11 and 12, 13 and 14 respectively, which are adapted for electrical engagement upon attachment of the sections 8 and 9. As here shown, the section 8 is particularly designed as a stationary socket which may be affixed to a wall or base board or electric panel or the like, while the section 9 is in the form of a plug and is arranged for use at the end of a flexible electric conductor. However, as will be understood, both of the sections may be connected to the ends of flexible electric conductors for use in an extension circuit or both of the sections may be secured to relatively fixed mountings but arranged for movement to and from each other.

As an important feature of the present invention, the section 9 is provided with a guide 16 which is longitudinally extended from an end or side 17 of the section and is adapted for engagement in an opening or guideway 18 in an opposed end 19 of the section 8. Preferably the guide 16 is substantially centrally positioned between the contact members 13 and 14, which also extend longitudinally from the end 17 in substantially parallel relation to the guide 16, and the member 8 is provided with openings 21 and 22 in registration with the contact members 11 and 12 for insertion through the openings of the contact members 13 and 14 for engagement of the latter with the contact members 11 and 12. Preferably, the distal end 20 of the guide 16 is extended longitudinally somewhat beyond the distal ends 23 and 24 of the contact members 13 and 14, so that the guide end 20 may be inserted in the guide opening 18 prior to the engagement of the contact member ends 23 and 24 with the end surface 19 of the section 8, so as to align the sections 8 and 9 for attachment. Upon insertion of the guide end 20 in the guide opening 18, the section 9 may be rotated until the contact member ends 23 and 24 fall into the openings 21 and 22 of the section 8, when the section 9 may be displaced longitudinally to effect an insertion of the contact members 13 and 14 through the openings 21 and 22 for engagement with the contact members 11 and 12 of the section 8. In this manner the attach-

ment of the section is greatly facilitated for it is only necessary to locate the guide end 20 in the guide opening 18 and then rotate the section 9 and displace the same longitudinally, and these operations may be quickly and simply effected without the coacting openings and parts being visible to the person effecting the attachment, the entire operation of attachment being easily effected by the sense of feeling rather than sight.

The section 8 in the present embodiment is formed of a body preferably molded from plastic insulation material or the like and arranged with an interior chamber 25 in which the contact members 11 and 12 may be mounted, and is provided with a central core portion 26 through which the guide opening 18 may be formed. The contact members 11 and 12 are here shown in the form of flat, resilient metal strips which are fixed at their ends 27 and 28 to the body of the section by means of terminal screws 29 and 31 which may be used to electrically connect the ends of electric conductors to the contact members. The contact members 11 and 12 are folded longitudinally from the ends 27 and 28 towards the end 19 of the section to position portions 32 and 33 of their length against the side wall of the chamber 24, and are folded adjacent the end 19 to provide free longitudinal portions 34 and 35 in substantial alignment with the openings 21 and 22 for engagement with the longitudinal contact members 13 and 14 upon attachment of the sections.

The section 9 is preferably also formed of a body molded from plastic insulation material so that the body and guide 16 may be formed as an integral unit. As one of the important features of the present invention in providing for an improved sturdiness and rigidity of construction of the section 9, the contact members 13 and 14 of that section are supported not only in the body of the section, but also on the longitudinal guide 16, so that an extremely rigid longitudinal unit is formed by the contact members and the guide. By reason of this arrangement, there is little or no possibility for the contact members 13 and 14 to become poorly spaced or aligned with respect to the openings 21 and 22 in the section 8, even though the plug section is frequently subjected to rather rough usage. As here illustrated, in Figures 1, 2 and 3, the contact members 13 and 14 are formed of flat metallic strips which are secured at their end portions 37 and 38 to a transverse wall 39 in the body of the plug 9, by means of fastening screws 41 and 42 and terminal screws 43 and 44. From the end portions 37 and 38 the contact members are bent longitudinally so as to lie at opposite sides of the guide 16 and are arranged with the greatest transverse dimension of the strips substantially radially of the guide so as to provide a maximum resistance to bending of the sections radially of the guide. The distal ends 23 and 24 are as here shown, supported directly on the guide 16 by providing such ends with lateral projections 46 and 47 and extending such projections directly into the body of the guide 16.

To accommodate the extension of the lateral or radial width of the contact members 13 and 14 through the end 19 of the section 8, the latter is preferably formed with a cross-slot 48 connecting the guide opening 18 with the openings 21 and 22, so that the ends 23 and 24 of the plug contact members may be extended through the slot 48 on attachment of the sections. To fur-

ther assist in the ease of attachment of these sections, the ends 23 and 24 of the plug contact members are preferably beveled towards the guide 16 so as to provide the greatest longitudinal extension of the contact members at the plug, whereby the ends of the contact members may be more readily aligned with the cross-slot for attachment of the plug. It will also be understood that the coaction of the cross-slot 48 and the transverse ends 23 and 24 of the plug contact members affords a stop for the rotative movement of the plug in a position properly aligning the contact members 13 and 14 with the openings 21 and 22. To further facilitate the attachment of the sections, the distal end 20 of the guide may be rounded as here shown, and also preferably, the guide opening 18 is enlarged somewhat at the end 19 of the section 8 to assist the quick locating of the guide end therein.

Preferably, the openings 21 and 22 in the section 8 are of substantially rectangular shape in cross-section and spaced by a distance which is standard in the manufacture of this type of electric connectors, so that the section 8 may be used as a socket for a more or less conventional type of plug when desired.

A slightly modified form of the invention has been illustrated in Figures 5 and 6 of the drawing, wherein the contact members 13' and 14' of the plug section 9' are arranged at opposite sides of the guide 16' in spaced relation thereto and disposed with the greatest width of the sections in planes spaced from and substantially parallel to the axis of the guide 16', rather than substantially radially thereto as in the first embodiment. In order to support the contact members 13' and 14' on the guide 16', the latter is provided with a pair of radially extending webs or lateral side strips 49 and 51, which are engaged along their outer longitudinal sides by the contact members 13' and 14'. The form of the plug described may be used with a coacting section 8' as described in connection with the first embodiment, in view of the relative shape and spacing of the openings 21 and 22 above described, and the provision of the cross-slot 48. In the form of the invention illustrated in Figures 5 and 6, a somewhat greater area of electric contact is provided between the plug contact members 13' and 14' and the contact members 11' and 12' of the section 8'. We claim:

1. A sectional electric connector comprising, a body having a guide opening in a side thereof and a plurality of openings spaced radially from said guide opening and a slot connecting said openings, a plurality of resilient contacts mounted within said body in registration with said second named openings and adapted to be forced outwardly of said guide opening, a second body having a side facing said first body, a guide extending from said second body side and adapted for longitudinal and rotational engagement with said guide opening, a plurality of electric contact members extending from and supported by said second body side in substantially parallel relation to said guide and substantially radially therefrom, means extending between said contact members and said guide to prevent inward deflection of said contact members on engagement with said resilient contacts, said guide and contact members being adapted for insertion through said slot and second named openings for engagement with said resilient contacts.

2. A sectional electric connector of the character described comprising, a body having a

central opening and a plurality of diametrically opposed openings connected to said central opening by a slot, said diametrically opposed openings arranged to receive the contact arms of a standard plug, resilient electric contacts mounted within said body at the inner ends of said diametrically opposed openings and positioned for engagement by said arms when inserted in said diametrically opposed openings, a second body 5 having a guide extending from a side thereof and adapted for longitudinal and rotational engagement in said central opening, a plurality of contact members supported at one end by said second body and extending substantially the full 10 length of said guide and held against inward deflection thereby, said members arranged to engage in said slot and diametrically opposed openings and extending radially from said guide to engage at their outer edges with said resilient 15 contacts upon engagement of said second body member with said first body member.

3. A sectional electric connector comprising, a body member having a central opening and a 20 plurality of openings spaced therefrom and arranged to receive the contact arms of a standard plug, said body having slots radiating from and connecting said central opening with said other openings, contact members in said body member located within said second openings, a second body member, a guide having a substantially cylindrical free end and extending from a side thereof and adapted for engagement in said central opening of said first body member, contact members on said second body member movable through said slots and engageable with the contact members in said second openings, said guide and body member being formed and arranged whereby rotation of the member will be 15 permitted during the initial engagement of said guide in said central opening and prevented when the contact members are engaged, said guide being of such size and form as to preclude its entry into either said slots or said second openings. 20
